(57) **CLAIM**

The ornamental design for a container with handle, as shown and described.

DESCRIPTION

FIG. 1 is a perspective view of a container with handle, showing my new design;

FIG. 2 is a left side elevational view thereof;

FIG. 3 is a rear elevational view thereof;

FIG. 4 is right side elevational view thereof;

FIG. 5 is front elevational view thereof;

FIG. 6 is a top plan view thereof; and,

FIG. 7 is a bottom plan view thereof.

The broken line portions show unclaimed subject matter only and form no part of the claimed design.

1 Claim, 4 Drawing Sheets

FIG. 1

FIG. 2***FIG. 3***

FIG. 4***FIG. 5***

FIG. 6***FIG. 7***
